(57) **CLAIM**

The ornamental design for a retainer clip removal tool, as shown and described.

DESCRIPTION

FIG. 1 is a front elevational view of the retainer clip removal tool showing my novel design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view of the retainer clip removal tool of the present invention;

FIG. 8 is a reversed perspective view of the retainer clip removal tool of the present invention; and,

FIG. 9 is a perspective view of the retainer clip removal tool of the present invention shown disengaging a clip from a bicycle chain.

The broken lines shown in FIG. 9 are for illustrative purposes only and form no part of the overall claimed design.
